Des. 229,812

Patented Jan. 8, 1974

229,812

DISPOSABLE PLASTIC DISH

Paul Davis, Swampscott, Mass., assignor to Sweetheart
Plastics, Inc., Wilmington, Mass.

Filed Jan. 31, 1972, Ser. No. 222,428

Term of patent 14 years

Int. Cl. D7—01

U.S. Cl. D7—1

FIG. 1

FIG. 2

FIG. 3

FIG. 4

FIG. 5

FIG. 6

FIG. 1 is a top view of a disposable plastic dish showing my new design;

FIG. 2 is a bottom view thereof;

FIG. 3 is a side view, partly in section, thereof;

FIG. 4 is a top view of a second embodiment of a disposable plastic dish showing my new design;

FIG. 5 is a bottom view thereof; and

FIG. 6 is a side view, partly in section, thereof.

The basket weave pattern shown in FIGS. 1, 2, 4 and 5 extends about the full flange of the design.

I claim:

The ornamental design for a disposable plastic dish, as shown and described.
